UNITED STATES PATENT OFFICE.

FRITZ GUYE, OF NEUCHATEL, SWITZERLAND.

SELF-WINDING CLOCK.

1,371,164.

Specification of Letters Patent.

Patented Mar. 8, 1921.

Application filed April 25, 1919. Serial No. 292,669.

To all whom it may concern:

Be it known that I, FRITZ GUYE, a citizen of the Swiss Republic, residing at Neuchatel, Switzerland, have invented certain new and useful Self-Winding Clocks, of which the following is a specification.

The invention relates to self winding clocks, and more particularly to apparatus of the kind wherein mechanism is provided for closing the circuit of an electric motor to cause the re-tensioning of the spring and for breaking the said circuit after the spring has stored sufficient power to drive the clock for a given length of time.

Two disadvantages attaching to the majority of such devices as previously proposed are, firstly, that they cannot be connected to any electricity supply which happens to be available as, for instance, the electric light and power mains whose voltage is such that the body of the clock cannot be connected to them without risk of danger to the persons who have to set and clean the clocks; and, secondly, that no provision is made for permitting the clock to continue operating in the event of a stoppage of the electricity supply at the moment when the motor circuit is closed for the purpose of re-winding the spring.

The object of the present invention is to provide an improved apparatus of the kind above set forth wherein by the employment of a comparatively small cam the spring is wound up a considerable number of revolutions so that, with but one winding operation, sufficient energy will be imparted to the driving spring to actuate the clock for a comparatively long period of time.

With this object in view, the invention consists in an automatic apparatus for winding spring-driven clocks of the kind hereinbefore described, comprising a rotatable sleeve of conducting material, a pair of contact members engaging said sleeve but normally electrically insulated therefrom, means whereby the actuation of the spring winding mechanism causes rotation of the sleeve and the positive electrical connection of the said contact members during approximately one revolution of the sleeve, a controlling cam, a motor-circuit make and break device engaging said cam, means rotatable by the winding mechanism to rotate said cam periodically during the rotation of said mechanism, a rotatable element associated with the cam, and means rotatable by the expansion

of the driving spring for periodically rotating the cam through the medium of the said rotatable element.

The invention further consists in the arrangement and combination of parts substantially as hereinafter described and more particularly pointed out in the appended claims.

In the accompanying drawings which illustrate a convenient embodiment of the present invention:—

Figure 1 is a diagrammatic elevation of the essential parts of the improved apparatus;

Fig. 2 is a diagram of the electrical connections;

Fig. 3 is a detail plan view, and

Fig. 4 is a front elevation of the controlling cam.

Referring to Fig. 1 of the drawings:—*a* is the plate of the clock. The barrel *b* is rotatably mounted on an arbor *c* supported by the plate *a*. The spring contained in the barrel is shown diagrammatically at 5 and 80 is wound up by means of the barrel drum through a train of gearing 6 from a worm *d* arranged in the prolongation of the axis of the electric motor *e* connected to the electric supply as shown in Fig. 2. The barrel 85 by means of a train of gearing 7 drives a split sleeve *f* which is rotatably mounted on an arbor 8. The sleeve *f* is split to form a notch 9 in which, in the normal position, the projecting ends of two spring contact 90 pieces *g* are adapted to engage. Only one of the contact pieces *g* is shown in the drawings. The three surfaces of the notch 9 are lined with insulating material, so that the ends of the contacts *g*, when resting in the 95 notch, are electrically insulated from the sleeve *f* and arbor 8. The contact pieces *g* are connected to the motor circuit through terminals 1, 2 (Fig. 2).

The drum of the barrel *b* carries a stud *b'* 100 which engages once during each revolution of the barrel with a pin wheel *h* (Figs. 1 and 3). On the shaft of this pin wheel there is fixed a cam *i* of insulating material. On the periphery of this cam is 105 adapted to bear the nose *j* of a lever fulcrumed at *j'*. At the end of this lever farthest from its nose *j* is provided a contact piece *k*. A spring 10 is attached at one end to the lever and gives the contact piece *k* 110 a constant tendency to press against another contact piece carried by a strip *l* which is

electrically connected to the motor by means of a terminal 3 (Fig. 2). The parts carrying the lever and the strip *l* are electrically insulated from each other and both parts 5 are electrically insulated from the clock plate.

The terminal 4 is in metallic connection with the lever *j*, so that the spring 10 in acting upon the latter has a tendency to 10 close the contact and through it the motor circuit, but the contact is only closed when the nose *j* bears on the depressed part of the cam *i*.

A star wheel *m* is provided with a central 15 boss loosely mounted on an arbor fixed in the clock plate. This wheel is normally held in engagement with the wheel *h* by a spring *n*. The wheel *m* overlaps the barrel *b* and its teeth normally lie in the path of an 20 arm *c'* fixed to the arbor of the barrel. On the periphery of the box of the barrel there is provided an inclined plane *b*² which, in the rotation of the barrel, moves the star 25 wheel *m* axially against the action of the spring *n*, and thus disengages the star wheel from the wheel *h*.

The displaced position of the star wheel *m* is shown dotted in Fig. 3.

The improved apparatus operates as follows: When the clock is to be set going, the cam *i* is rotated until the nose *j* lies at 30 the end 11 of the recess in the cam *i*. In this position the terminals 3 and 4 are connected electrically, and the motor, being connected to the electric supply, acts upon the train of gearing 6 so as to wind the driving spring 5 of the clock by means of the barrel *b*, which is rotated in the direction indicated by the arrow 12. At each revolution 35 of the latter the finger *b'* engages with the pins of the wheel *h* and shifts the latter one step, while the inclined plane *b*² raises the wheel *m* out of engagement with the wheel *h* and therefore out of the path of the finger *b'*.

As soon as the barrel begins to revolve, the socket *f* through the gearing 7 rotates also. This causes the contacts *g* to ride up on to the sleeve *f*, thereby electrically connecting the contacts *g* and terminals 1 and 2. The motor *e* is thus connected to the electric supply in parallel with the terminals 3 and 4. The result of this is that this motor revolves until the strips *g* have been 50 brought back into the notch of the sleeve *f* so as to interrupt the connection between terminals 1 and 2.

The barrel has now made six revolutions and the spring 5 is wound to drive the clock 55 for twenty-four hours. Since the nose *j* is still in the recess of the cam *i* and the contact *k* still maintains the connection between the terminals 3 and 4, the motor *e* continues to rotate and causes the contacts *g* again to 60 ride out of the notch 9 and electrically con-

nect the terminals 1 and 2. When the contacts *g* have been thus moved out of the notch 9, the end 13 of the cam recess passes the nose *j* and causes the lever to swing on the pivot *j'* and break contact between the terminals 3 and 4. The barrel *b* then continues to rotate until the sleeve *f* has completed another revolution and the terminals 1 and 2 are again disconnected by the contacts *g* falling into the notch 9. The 75 spring 5 has now been wound to keep the clock running for forty-eight hours.

At each winding the barrel *b* makes a complete number of revolutions; so that after winding, the barrel *b* always stops in 80 such a position that the inclined plane *b*² and the stud *b*¹ are clear of the star wheel *m*.

The spring 5 now slowly unwinds and rotates the arbor in the usual manner in the direction of the arrow 12. During each revolution of the arbor the finger *c'* revolves the star wheel *m* one step in a clockwise direction, and after the clock has been running for twenty-four hours the wheel *m* will have been rotated six steps by the finger *c'*. Each 90 movement of the wheel *m* causes an anticlockwise movement of the wheel *h* and cam *i* and, after six of such movements, the nose *j* falls into the cam recess at the end 13 and causes the contact *k* to connect the terminals 95 3 and 4.

If current is flowing in the supply leads at the moment when the nose *j* falls into the recess of the cam *i*, the motor will cause the barrel to rotate and the contacts *g* to leave 100 the notch 9 as before described, and the spring 5, still possessing a reserve tension for twenty-four hours, will be rewound by another six revolutions of the barrel, to raise its tension again to that necessary for driving the clock for 48 hours. Immediately 105 after the contacts *g* leave the notch 9 and connect the terminals 1 and 2, the cam *i* will be rotated in a clockwise direction and lift the nose *j* on to the higher surface of 110 the cam, thereby disconnecting the terminals 3 and 4. When the sleeve *f* has completed one revolution the contacts *g* will fall into the notch 9 and disconnect the terminals 1 and 2.

If no current is flowing in the supply leads at the moment when nose *j* falls into the cam recess after the clock has been running for twenty-four hours, the contact *k* will connect the terminals 3 and 4, but the 120 barrel will not be rotated since no current is available for running the motor *e*. The reserve tension of the spring 5 will now operate the clock mechanism until the supply of current is restarted. In the period during 125 which the reserve tension is being utilized, the nose *j* remains in the cam recess and the contact *k* therefore maintains electrical connection between the terminals 3 and 4, so that immediately the current is 130

again switched on, the motor will rotate the barrel and cause a rewinding of the spring 5 for running the clock for a period between twenty-four and forty-eight hours, depending upon the position occupied by the nose *j* with respect to the end 11 of the cam recess at the moment when the current re-commences flowing in the supply leads.

In order to avoid any over-straining of 10 the spring, the latter is arranged inside the barrel in such a manner that it is able to slip over the barrel drum when it has attained its maximum tension. This winding mechanism is applicable to clocks having a staff 15 escapement, as well as to pendulum clocks. It is also possible to arrange the various parts in such a manner as to cause the winding to take place, for instance, every forty-eight hours, so that the clock will be wound 20 to go for seventy-two hours when its spring movement is fully wound up.

Having now described my invention, what I claim as new and desire to secure by Letters Patent is:—

25 1. An automatic apparatus for winding spring-driven clocks of the kind hereinbefore described, comprising a rotatable sleeve of conducting material, a pair of contact members engaging said sleeve but normally electrically insulated therefrom, means whereby the actuation of the spring winding mechanism causes rotation of the sleeve and the positive electrical connection of the said contact members during approximately one revolution of the sleeve, a controlling cam, a motor-circuit make and break device engaging said cam, means rotatable by the winding mechanism to rotate said cam periodically during the rotation of 35 said mechanism, a rotatable element associated with the cam, and means rotatable by the expansion of the driving spring for periodically rotating the cam through the medium of the said rotatable element.

45 2. An automatic apparatus for winding spring-driven clocks of the kind hereinbefore described, comprising a rotatable sleeve of conducting material, a pair of contact members engaging said sleeve but normally electrically insulated therefrom, means whereby the actuation of the spring winding mechanism causes rotation of the sleeve and the positive electrical connection of the said contact members during approximately one revolution of the sleeve, a controlling cam, a motor-circuit make and break device engaging said cam, means rotatable by the winding mechanism to rotate said cam periodically during the rotation of 50 said mechanism, a rotatable star wheel engaging a pin wheel secured on the spindle of the cam, and means rotatable by the expansion of the driving spring for periodically rotating the cam through the medium of the said star and pin wheels.

55 3. An automatic apparatus for winding spring-driven clocks of the kind hereinbefore described, comprising a rotatable sleeve of conducting material, a pair of contact members engaging said sleeve but normally electrically insulated therefrom, means whereby the actuation of the spring winding mechanism causes rotation of the sleeve and the positive electrical connection of the said contact members during approximately one revolution of the sleeve, a controlling cam, a motor-circuit make and break device engaging said cam, means rotatable by the winding mechanism to rotate said cam periodically during the rotation of 60 said mechanism, a rotatable star wheel engaging a pin wheel secured on the spindle of the cam, and means rotatable by the expansion of the driving spring for periodically rotating the cam through the medium of the said star and pin wheels.

3. An automatic apparatus for winding spring-driven clocks of the kind hereinbefore described, comprising a rotatable sleeve of conducting material, a pair of contact members engaging said sleeve but normally electrically insulated therefrom, means whereby the actuation of the spring winding mechanism causes rotation of the sleeve and the positive electrical connection of the said contact members during approximately one revolution of the sleeve, a controlling cam, a motor-circuit make and break device engaging said cam, means rotatable by the winding mechanism to rotate said cam periodically in one direction during the rotation of said mechanism, a rotatable star wheel engaging a pin wheel secured on the spindle of the cam, and means rotatable by the expansion of the driving spring for periodically rotating the cam in the opposite direction through the medium of the said star and pin wheels.

4. An automatic apparatus for winding spring-driven clocks of the kind hereinbefore described, comprising a rotatable sleeve of conducting material, a notch in said sleeve having insulated surfaces, a pair of contact members normally engaging in said notch, means whereby the actuation of the spring winding mechanism causes rotation of the sleeve and the pair of contact members to engage the conducting surface of the sleeve until the sleeve has rotated sufficiently to allow the contact members to fall again into the notch, a controlling cam, a motor-circuit make and break device engaging said cam, means rotatable by the winding mechanism to rotate said cam periodically in one direction during the rotation of the said mechanism, a rotatable star wheel engaging a pin wheel secured on the spindle of the cam, and means rotatable by the expansion of the driving spring for periodically rotating the cam in the opposite direction through the medium of said star and pin wheels.

5. An automatic apparatus for winding spring-driven clocks of the kind hereinbefore described, comprising a rotatable sleeve of conducting material, a notch in said sleeve having insulated surfaces, a pair of contact members normally engaging in said notch, means whereby the actuation of the spring winding mechanism causes rotation of the sleeve and the pair of contact members to engage the conducting surface of the sleeve until the sleeve has rotated sufficiently to allow the contact members to fall again into the notch, a controlling cam, a motor-circuit make and break device engaging said cam, a projection rotatable with and carried by the spring barrel, a pin wheel secured on the spindle of the cam and receiving periodic rotation from said projections to rotate said cam per-

- riodically in one direction during the rotation of the said barrel, a rotatable star wheel normally engaging said pin wheel, and an arm carried by the barrel arbor and rotatable by the expansion of the driving spring for periodically rotating the cam in the opposite direction through the medium of said star and pin wheels.
6. An automatic apparatus for winding 10 spring-driven clocks of the kind hereinbefore described, comprising a rotatable sleeve of conducting material, a notch in said sleeve having insulated surfaces, a pair of contact members normally engaging in said 15 notch, means whereby the actuation of the spring winding mechanism causes rotation of the sleeve and the pair of contact members to engage the conducting surface of the sleeve until the sleeve has rotated sufficiently to 20 allow the contact members to fall again into the notch, a controlling cam, a motor-circuit make and break device engaging said cam, a projection rotatable with and carried by the spring barrel, a pin wheel secured 25 on the spindle of the cam and receiving periodic rotation from said projection to rotate said cam periodically in one direction during the rotation of the said barrel, a rotatable star wheel normally engaging said 30 pin wheel, an arm carried by the barrel arbor and rotatable by the expansion of the driving spring for periodically rotating the cam in the opposite direction through the medium of said star and pin wheels, and an 35 inclined plane carried by the barrel for lifting the star wheel out of engagement with the pin wheel in the period during which the pin wheel is being rotated by the projection on the barrel.

being rotated by the projection on the barrel.

7. An automatic apparatus for winding 40 spring-driven clocks of the kind hereinbefore described, comprising a rotatable sleeve of conducting material, a notch in said sleeve having insulated surfaces, a pair of contact members normally engaging in said notch, 45 means whereby the actuation of the spring winding mechanism causes rotation of the sleeve and the pair of contact members to engage the conducting surface of the sleeve until the sleeve has rotated sufficiently to 50 allow the contact members to fall again into the notch, a controlling cam, a motor-circuit make and break device engaging said cam, a projection rotatable with and carried by the spring barrel, a pin wheel secured 55 on the spindle of the cam and receiving periodic rotation from said projection to rotate said cam periodically in one direction during the rotation of the said barrel, a rotatable star wheel normally engaging said 60 pin wheel, an arm carried by the barrel arbor and rotatable by the expansion of the driving spring for periodically rotating the cam in the opposite direction through the medium of said star and pin wheels, and an 65 inclined plane carried by the barrel for lifting the star wheel out of engagement with the pin wheel in the period during which the pin wheel is being rotated by the projection on the barrel.

In testimony whereof I have signed my name to this specification.

FRITZ GUYE.
